CLAIM

The ornamental design for a golf mat, substantially as shown and described.

DESCRIPTION

FIG. 1 is a perspective view of a new, original, and ornamental design of a golf mat in accordance with the present invention;

FIG. 2 is a top side plan view of the design of FIG. 1; FIG. 3 is a bottom side plan view of the design of FIG. 1; FIG. 4 is a left side elevation view of the design of FIG. 1; FIG. 5 is a right side elevation view of the design of FIG. 1; FIG. 6 is a front side elevation view of the design of FIG. 1; and,

FIG. 7 is a rear side elevation view of the design of FIG. 1. The portions shown in broken lines in the Figures form no part of the claimed design.
